H. E. HILE

PLUMBER'S ACID CAN

Filed March 1, 1926

UNITED STATES PATENT OFFICE.

HARLAN E. HILE, OF LATROBE, PENNSYLVANIA.

PLUMBER'S ACID CAN.

Application filed March 1, 1926. Serial No. 91,526.

The present invention relates to a combined receptacle in the form of two cans, one mounted on the other, the lower can being adapted for the reception of a wet cloth 5 upon which a soldering iron may be wiped and the upper can being adapted for the reception of acid used in soldering.

A very important object of the invention is to provide an improved acid can having a 10 threaded lid provided with a depending tube into which a brush may be placed for contact with the acid, said tube preventing the spilling of the acid should the can be knocked over.

Another important object of the invention is to provide a can for the reception of a wet cloth, said can being provided with a side opening having a slidable closure so that easy access may be had to the cloth in 20 the can with a soldering iron, so that the soldering iron may be wiped off conveniently.

A still further very important object of the invention is to provide a can having a cover provided with an annular seat on the 25 exterior thereof for the reception of an acid can.

Another object of the invention is to provide a device of this nature which is possessed of a simple and efficient construction, 30 one which will prove thoroughly reliable in use, and otherwise well adapted to the purpose for which it is designed.

With the above and numerous other objects in view as will appear as the description 35 proceeds, the invention resides in certain novel features of construction, and in the combination and arrangement of parts as will be hereinafter more fully described and claimed.

In the drawing:—

Fig. 1 is an elevation of the device embodying the features of my invention, and

Fig. 2 is a vertical section therethrough.

Referring to the drawing in detail it will be seen that 5 designates a can adapted to receive a wet cloth 6. The can 5 is provided with an opening 7 having edge beads 8 for slidably receiving the edges 9 of a closure 10. A cover 11 is disposed over the upper open end of the can 5, and has an annular cup shaped receptacle or seat 12 mounted exteriorly thereon. An acid can 13 is dis-

posed in the seat 12 and at its upper end is provided with an inwardly extending flange 14 terminating in a rising and threaded collar of annular construction shown at 14 for threadedly receiving the collar 15 of a cap 16 which is provided with a depending tube 17 terminating in the can 13 adjacent the bottom.

This can 13 is adapted to receive acid which is used in soldering and should be about one-third full. A pocket 18 is provided exteriorly of the can 13 for holding an acid brush when the same is not in use.

It will be seen from the above description that I have provided an exceedingly compact and convenient device for use by plumbers in soldering operations. The parts of the device are very accessible, and capable of easy and expeditious assembly and disassembly.

The present embodiment of the invention has been disclosed in detail since in actual practice it attains the features of advantage 75 enumerated as desirable in the statement of the invention and the above description.

It is apparent that changes in the details of construction, and in the combination and arrangement of parts may be resorted to 80 without departing from the spirit or scope of the invention as hereinafter claimed or sacrificing any of its advantages.

Having thus described the invention, what I claim as new and desire to secure by Letters Patent is:—

A plumber's soldering accessory, including, in combination, a can adapted to receive a wet rag and having an opening in the side wall thereof provided at its edges with beads, a closure slidable on said beads across the opening, a cover removably mounted on the upper end of the can, a cup-shaped seat mounted on the exterior of the cover, an acid can seated in said seat and having an in-turned flange at its upper end terminating in a rising annular threaded flange, a cap engaged with the said threaded flange and provided with a depending tube terminating in the acid can adjacent the bottom thereof, and a pocket formed on the exterior of the acid can for holding a brush.

In testimony whereof I affix my signature.
HARLAN E. HILE.
